UNITED STATES PATENT OFFICE.

SAMUEL S. GIORDANO, OF ROCKFORD, ILLINOIS.

MOVING-PICTURE MACHINE.

986,163.

Specification of Letters Patent. Patented Mar. 7, 1911.

Application filed March 17, 1910. Serial No. 550,057.

To all whom it may concern:

Be it known that I, SAMUEL S. GIORDANO, a subject of the King of Italy, residing at Rockford, in the county of Winnebago and 5 State of Illinois, have invented certain new and useful Improvements in Moving-Picture Machines, of which the following is a specification.

The object of this invention is to construct 10 a moving picture machine which will eliminate, to a considerable extent, the vibration of the pictures when projected upon a screen.

In the accompanying drawings, Figure 1 is a vertical section on dotted line *d d* 15 Fig. 2. Fig. 2 is a side elevation in which portions are broken away. Fig. 3 is a section on dotted line *b b* Fig. 1. Fig. 4 is a top view. Fig. 5 is a section on dotted line *c c* Fig. 1. Fig. 6 is a section on dotted line 20 *a a* Fig. 1. Fig. 7 is a partial face representation. Fig. 8 is a section on dotted line *c e* Fig. 1. Fig. 9 is a face representation of the plates 26 and 27.

The main frame comprises the side plates 25 1 held suitably separated by the cross bars 2, and the frame is supported upon the stand 3. The side plates support a main shaft 4 which is rotated, in this instance, by the crank 5. This shaft 4 has a spur gear 6 fixedly connected to it. A shaft 7 is supported by the side plates 1, and has a spur pinion 8 fixedly connected to it and meshes 30 with the spur gear 6. A spur gear 9 has a fixed connection with the shaft 7, and meshes with a spur pinion 10 secured to the shaft 11, supported by the side plate 1. A rod 12 is fixedly supported by the side plates 1 and has two toothed drums 13 and 13' 35 loosely mounted thereon and held against bodily lengthwise movement on the rod 12 by the collars 14. To the toothed drums and integral therewith are formed star wheels 15 and 15' provided with radial slots 16 and 16' respectively. To the shaft 7 are 40 fixedly connected two cut away cams 17 and 17' and to each cam is secured a yoke 18 and 18' respectively having a cross bar 19 and 19' respectively at its outer end. As the shaft 4 is rotated by the crank 5, the 45 cross bars 19 and 19' will enter the slots 16 and 16' of the star wheels thereby imparting an intermittent rotary movement to the star wheels, and to the toothed drums 13 and 13'. The yokes 18 and 18' are set opposite one 50 another so that one toothed drum remains

stationary during the movement of the other drum, and the cams 17 and 17' being received in the curved or hollow portions of the star wheels will prevent the movement of the star wheels until moved by the cross 60 bars 19 and 19' of the yokes 18 and 18'.

Adjacent to the rod 12, is a rod 20 upon which are located two grooved rollers 21 and 21' which are in line with the toothed drums 13 and 13'. The teeth of the drums are 65 received in the grooves of the rollers. To the upper portion of the side bars 1 of the frame are secured brackets 22 which support a rod 23, and it supports two spools 24 and 24' which turn thereon. To the upper portion of the side bars 1 of the frame is secured a plate 25 having an upturned end 26. This upturned end 26 supports a plate 27 which is spaced therefrom by the blocks 28. Each spool 24 and 24' has a tape 70 film 29 and 29' wound upon it, and the films pass between the toothed drums 13 and 13', and the grooved rollers 21 and 21', the teeth of the drums entering perforations in the 75 films, and as the toothed drums are intermittently rotated, the films will be intermittently moved vertically between the plates 26 and 27, and downwardly. The plates 26 and 27 are formed with openings 30 and 31 80 respectively. The plate 25 supports two objective lenses 32 and 32' which are adjusted on the bolt 33 through the seat, and bolt 34 so as to focus them at a common point.

The shaft 11 has a cut away cam 35 secured to it, and to this cam is secured a yoke 90 36 supporting a rod 37 at its free end. A shaft 38 is supported in the side plates 1 of the frame, and to it is secured a star wheel 39 provided with radial slots 40. The rod 37 of the yoke 36 enters the radial slots 40 of the star wheel 39, thereby imparting an 95 intermittent rotary movement to the shaft 38.

To the shaft 38 are secured two cams 41 and 41'.

A rod 42 is supported by the side plates 1, 100 and to this rod is fixedly connected a shutter, comprising the end plate 43 having two openings 44 and 44', and side bars 45 and 45' which are fixedly connected to the rod 42. The end of the side bar 45 has a depending 105 end 46 which is located against the outer face of one of the cams 41 as shown at Fig. 6, and the other side bar 45' of this shutter has a depending end 47 which is located adjacent the inner face of the other cam 41' as 110

shown at Fig. 3. The two cams 41 and 41' are set with their larger portions opposite, and the two depending ends 46 and 47 which are moved by these cams will impart a positive oscillatory movement to the end 43 of the shutter. The two openings 44 and 44' in the shutter are located one above the other, while the two openings 30 and 31 in the plates 26 and 27 respectively are located 10 in the same horizontal plane.

From the frame depend two arms 48 to which is pivoted a rod 49. To this rod 49 is fixedly connected a bar 50. The upper end of this bar 50 is formed with a fork 51 15 which receives an eccentric 52 fixedly connected to the shaft 7. The lower end of this bar 50 has a dog 53 pivotally connected to it, and a spring 54 exerts its influence upon the dog to hold it yieldingly in an upward direction. From the frame depend two projections 55 which support a rod 56 in a fixed manner, and on this rod are mounted two yokes 57 and 57' in a pivotal manner. Each yoke supports a rod 58 and 58' respectively, 20 and each rod supports a spool 59 and 59' respectively. To each spool is fixedly connected a ratchet wheel 60 and 60' with which the dog 53 engages. From the yokes 57 and 57' rise projections 61 and 61' and each projection has a dog 62 and 62' pivoted to it and overlying the ratchet wheels 60 and 60' respectively. The films 29 and 29' are wound upon these spools 59 and 59' respectively.

During the rotation of the shaft 7, the eccentric 52 will rotate with it, which will oscillate the bar 50, and cause the dog 53 to engage the teeth of the ratchet wheels 60 and 60' thereby partially rotating the spools 59 and 59'. The dogs 62 and 62' will prevent 35 the backward movement of the spools.

The films are moved intermittently and one film remains at rest during the movement of the other film. The openings in the shutter will alternately expose the two 40 films, and when one film is covered, that film is being moved to present a new section of it.

By this arrangement two films are employed to present a continuous picture which is projected upon a screen by the two lenses 32 and 32' which are focused to a common point on the screen. 50

By the employment of two films, each containing one-half of the pictures of a given scene and exposing the pictures alternately of the films, the change from one film to the other is not apparent, as one picture is always on the screen, thereby the vibration of the pictures on the screen is practically obviated. 55

I claim as my invention. 60

1. In a moving picture machine, means for alternately actuating two coacting films, devices for projecting pictures from the films so actuated, a single pivotally mounted shutter that operates across both projecting devices and is provided with openings therethrough, said openings being disposed in a sequence to successively register with the projecting devices, and means for swinging the shutter back and forth on its pivot axis 70 to alternately expose the pictures of the different films. 65

2. In a moving picture machine, the combination with means for alternately actuating two coacting films, of lenses located side by side for projecting pictures from the films so actuated, an oscillatory shutter operating across said lenses and having openings disposed in a sequence to successively register with the lenses for effecting an alternate projection of the pictures, said shutter including a pair of swinging arms, a rotary shaft, and cams carried by the shaft and alternately operating on the arms to swing the same in opposite directions. 75 80 85

In testimony whereof I have hereunto set my hand in presence of two subscribing witnesses.

SAMUEL S. GIORDANO.
